UNITED STATES PATENT OFFICE.

WADE H. LOWRY, OF JACKSONVILLE, FLORIDA.

AERO SAFETY DEVICE.

1,037,943.

Specification of Letters Patent. Patented Sept. 10, 1912.

Application filed March 23, 1911. Serial No. 616,521.

To all whom it may concern:

Be it known that I, WADE H. LOWRY, a citizen of the United States, residing at Jacksonville, in the county of Duval and State of Florida, have invented certain new and useful Improvements in Aero Safety Devices; and I do hereby declare the following to be a full, clear, and exact description of the invention, such as will enable others skilled in the art to which it appertains to make and use the same.

This invention relates to improvements in safety appliances for aerial vehicles, the primary object of the invention being to provide means for controlling the descent in case of accident.

It has heretofore been known to employ a parachute on aerial vehicles, such as aeroplanes, but it has been found in practice that these parachutes do not always promptly open or become distended, a feature which renders their use, as heretofore employed, unreliable and unsatisfactory.

In carrying out the present invention, it is aimed to overcome this objectionable feature by providing means for automatically distending the lower edge, or open end, of the parachute, and at the same time releasing the parachute, so that the lower end is held rigidly distended, and the flexible supporting surface will immediately take the air from beneath.

My invention is not restricted to the exact details shown and described, but for the purpose of disclosure, reference is had to the accompanying drawings in which like characters designate the same parts in the several views, and in which,

Figure 1 shows my invention applied to a bi-plane, the parachutes being shown in operative position, controlling the descent of the machine; Fig. 2 is a similar view, showing the invention applied to a monoplane, in which construction of machine it is desirable to have a single parachute supporting the machine from a central position; Fig. 3 is a plan view of a bi-plane with the parachutes held in their folded position; Fig. 4 is a vertical central sectional view, showing one structure for containing and releasing the parachutes.

1 designates an aeroplane of any type, in Figs. 1 and 3 the type being illustrated as a bi-plane. In this construction of machine, there is arranged at opposite ends on the top of the top plane, a parachute which is held

in any suitable way against displacement in its folded position. As shown in detail in Fig. 4, one way consists of a cell or casing 3 containing a platform 4, provided with an aperture 5, and movably supported on a resilient member shown as a coiled spring 6. The parachute 2 is anchored to this casing through the cable 7, and when the parachute is in its folded position, it rests on a movable platform 4, which is forced down against the tension of the spring 6, the hinged cover 8 of the casing, being then swung over and latched by the spring operated bolts 9. These are mere details of structure, and may be readily modified to suit conditions. The cover 8 is closed against the action of the coiled spring 10.

The body or flexible skin of the parachute and its stay lines, may be of any suitable construction, but the lower edge of the flexible skin is provided with an annular inflatable tube 11, communicating through the flexible tube 12 and the piping 13, Fig. 3, with a tank 14 containing compressed air and provided with a suitable valve 15 for delivering the air from the tank to the inflatable tube 11. The tank, the valve, and the connections may be made of suitable material, and it will be understood that the flexible tube 12 is of sufficient length that there will be no strain thereon when the parachute is in its open position.

Any suitable means may be employed for operating the valve 15 and for simultaneously releasing the bolts 9. In the drawings the valve is shown as provided with a lever or handle 16 which may be operated in any suitable way by a cord or other device, terminating in a position adjacent the driver, and to this lever 16 is attached a pair of cables 17 reeving around suitably arranged pulley blocks 18, and connected with the bolts 9.

From Fig. 1, it will be seen that the line 100 of piping 13 extends from the tank 14 under the bottom of the top plane connecting with the flexible tube 12, as shown in Fig. 4.

In the use of a parachute with a monoplane, owing to the construction of the latter, the extensions being more or less unsupported, the strain would be too great if parachutes were located at each end of the machine, and in Fig. 2, I have shown my invention applied centrally to the machine.

In operation it will be observed that should the machine get beyond the control

of the driver and start to descend, upon operating the lever 16, the cables 17 shoot the bolts 9 for releasing the parachute, the same being shot upwardly and out of its casing by means of the spring operated platform 4. At the same time, valve 15 is opened and the compressed air rushes through the pipe-lines 13 and the flexible tube 12, immediately inflating the annular tube 11, and thereby opening the bottom of the parachute so that the web or body portion will immediately take the air; and it will be observed further that the base of the parachute is held rigidly distended not only by the action of the air from beneath, but also by the pressure from the compressed air tank 14, the latter being in communication with the annular tube the whole time the parachute is in operative position.

Having thus described my invention, the particular features of novelty will now be pointed out more succinctly in the following claims:—

1. In an aerial vehicle, the combination of a tank containing fluid under pressure, a parachute anchored to said vehicle and provided with an inflatable tube around its edge, a conduit closed to the atmosphere and leading from said tube to said tank, a valve controlling the admission of pressure fluid, from said tank to said tube, means for detachably holding said parachute against displacement, and means for releasing said parachute and simultaneously opening said valve, substantially as described.

2. The combination of an aerial vehicle, a tank thereon for containing fluid under pressure, a parachute provided with an annular inflatable tube around its edge, a conduit between said annular tubing and said tank, a valve controlling the fluid under pressure in said tank, latching means for detachably holding said parachute against displacement, and a cable connected at one

end to said valve and at its other end connected to said latching means, and means for operating said valve for releasing said latching means and inflating said annular tubing, substantially as described.

3. The combination of an aerial vehicle, a tank carried thereby for containing fluid under pressure, a movable platform carried by said vehicle, a parachute adapted to be folded upon said platform, said parachute being provided with an annular inflatable tube forming its base, latching means for holding said parachute and platform against displacement, means tending to force said platform and parachute upwardly against said latching means, a conduit between said inflatable tube and said tank, a valve interposed between said tank and conduit, means connected with said valve for releasing said latching means upon the movement of said valve, and means for operating said valve to inflate said tube upon said parachute being released and shot upwardly, substantially as described.

4. In an aerial vehicle the combination of an inflatable safety appliance anchored to said vehicle, and means for releasably holding said appliance in an inoperative position on said vehicle, with a compressed fluid tank, a valve connection between said tank and said inflatable appliance, whereby the compressed fluid from the tank may be discharged into the inflatable appliance, and the latter thus inflated, and means whereby the valve of the fluid tank is opened simultaneously with the releasing of the holding means of the safety appliance.

In testimony whereof, I affix my signature, in presence of two witnesses.

WADE H. LOWRY.
